ABSTRACT OF THE DISCLOSURE

A resistance winding is formed on an expanded split mandrel, and a split insulating shell surrounds and is bonded to the winding by a layer of thermosetting material. The bonding is accomplished by heating, and the mandrel is removed. The shell is fitted in a housing which has openings aligned with the slot in the shell, to permit terminals to be conductively connected to selected portions of the winding intermediate the edges of the slot.

This application is a continuation-in-part of our pending application, Precision Wire-Wound Electrical Resistance Windings and Method of Making Same, Ser. No. 402,510, filed Oct. 8, 1964, now abandoned.

Background of the invention

Field of the invention.—This invention relates to improvements in potentiometers, variable resistors and the like, and more particularly to an improved precision wire-wound electrical resistance winding and its method of manufacture.

Description of prior art.—In recent years, potentiometers and variable resistors have been developed which employ an “internal” design. In this design, a fine resistance wire is wound on a relatively large diameter supporting core of copper wire which is coiled in generally helical form. The movable wiper arm of the potentiometer or variable resistor is carried on a shaft within the helix and adapted to move longitudinally, upon relative rotation between the shaft and the helix, to contact the resistance wire at a selected point on a selected turn of the helix.

Compared with the conventional “external” design wherein the wiper arm is mounted for movement along the outside of the winding around a mandrel, the internal design permits potentiometers and variable resistors to be made which are much more compact, rugged and reliable, and lends itself to a greater degree of miniaturization and utility, where space and weight are at a premium.

Unfortunately, however, it is very difficult, by present methods, to accurately wind and mount such resistance windings within a housing. Also, presently known methods are sufficiently involved and unreliable that such structures cannot be made and sold except at considerable expense to both manufacturer and consumer.

In this latter connection, it has been attempted to form the helix as an integral part of a housing, as by potting a plastic material around the helix. When the potting material hardens, the result is a cylindrical housing with the helix embedded in its inner wall.

In such a procedure, it is not possible to achieve quantity production of windings of uniform size and electrical characteristics. One reason is the difficulties inherent in trying to coil each helix so that its turns are precisely the same size and have the same pitch, and in supporting the helix so that its turns remain so during pottng.

Still another problem is that of damage to the fine re-

2

sistance wire which frequently occurs in removing hardened potting material, as where terminals and tap connections must be made to winding at various points. To accomplish this requires that openings be made through the exterior of the housing to expose the wire at all points where connections are to be made. Several procedures have been practiced to make such openings, including grinding and blasting techniques. As will be appreciated, meticulous care is required to make an opening that will expose the wire without damage thereto. However, it frequently happens that the resistance wire is damaged, and there is a high rejection rate of resistance windings.

Summary of the invention

Our invention provides a simple, inexpensive, yet highly accurate method for manufacturing precision wound resistance windings for potentiometers and variable resistors employing the internal design, which can be repeated over and over again to uniformly produce resistance windings having the same structure and electrical properties. Our invention also provides a precision wound helical resistance winding with a slotted insulating shell bonded thereto, which facilitates electrically tapping the winding through a surrounding housing and the slot without damaging the resistance wire.

Brief description of the drawing

Description of preferred embodiments

To form the precision wound resistance winding of our invention, we utilize a novel manufacturing method em-

ploying a reusable, slotted winding mandrel 10. To produce the mandrel 10, a hole 12 is bored longitudinally through a sleeve 14 of hardenable tool steel, and a slot 16 the length thereof is cut in the sleeve. The slotted sleeve which was a cylinder to begin with, is then compressed with a suitable tool so that the slot 16 is closed. While thus compressed, the sleeve is heat treated, preferably to 55-56° Rockwell C. After being thus heat treated, the sleeve is of course a non-cylindrical element.

To complete the formation of the winding mandrel 10, the sleeve 14 is forced onto an arbor 18 having an outer diameter the same as the original inner diameter of the sleeve 14. The sleeve is thus expanded to a cylinder, and the slot 16 takes its original shape. Next, a helical groove 20 is precision ground in the outer surface of the cylinder 14 as by turning the arbor 18 on a lathe while grinding with a cutting piece. Preferably, the end faces of the sleeve 14 are undercut, as at 22, where the groove 20 begins and ends.

The arbor 18 also forms the work-piece for making the winding structure of our invention. In this connection, the arbor 18 is formed with a threaded end 19 of reduced diameter, and the split mandrel 10 is positioned on the arbor so that one end thereof is flush with the radial transition face 21 between the threaded portion 19 and the main body of the arbor. To aid in thus locating the mandrel, we provide a collar or ring 23 which is removably secured, as by a set screw, onto the arbor 18 a distance from the transition face 21 equal to the length of the split mandrel.

Referring to FIGURE 5, one end of an elongated wire-wound element 24 (e.g., a copper wire core on which fine resistance wire is helically wound in conventional fashion) is bent and located against the undercut portion of the mandrel 10 adjacent the ring 23. Then the element 24 is wrapped on the mandrel so that it fits in the groove 20, i.e., is formed into a helix, as by turning the arbor on a lathe while keeping the element 24 under tension. When the winding reaches the other end of the mandrel 10, the end of the element 24 is clamped against that end of the mandrel by a washer 25 which is held in place by a nut 27 on the threaded end 19 of the mandrel 18.

Having secured the element 24 around the mandrel 10, an insulating strip 26 of thermosetting material is wrapped around the outer surface of the element over the mandrel. Preferably, the strip 26 is a length of glass cloth which is impregnated with a thermosetting polyester resin. The length of the strip 26 is coextensive with the mandrel, i.e., it does not overlay the slot 16, whereby the ends of the strip define a slot 28 that is aligned with the slot 16. Also, the strip 26 includes holes, as at 30, through which to make external electrical connections to the wire-wound element 24 after the winding structure is completed.

After wrapping the strip 26 around the element 24, the combination is placed within and surrounded by a shell 32 of insulating material, e.g., a plastic material such as glass epoxy, and the shell 32 has a slot 34 the length thereof. The slot 34 allows the shell 32 to be radially expanded to fit snugly over the strip-covered mandrel and thereby hold the strip and the wire-wound element 24 firmly in place. The shell 32 also includes holes as at 36, and the shell is so oriented that its slot 34 is aligned with the slots 16, 28, and its holes 36 are aligned with the holes 30 in the strip 26.

Preparatory to heating, an element such as a rubber band may be placed around the shell 32 to aid in holding the parts in the assembled relation. The assembly is placed in an oven and heated, e.g., at about 150° C. for about forty-five minutes. The thermosetting material of the strip 26 softens and flows sufficiently to cover the surface of the wire-wound element 24 and the shell 32 which abut 65 the strip 26, and results in continuous fillets bridging the element and the strip. Upon cooling, the thermosetting material cures to bond the shell, the strip and the element 24 into a unitary structure.

The mandrel 10 and the winding structure are removed 75

from the arbor 18 by removing the collar 23, washer 25 and the nut 26. A suitable tool, such as a collar (not shown) having an outer diameter less than the outer diameter of the mandrel 10, is then slipped onto the arbor to engage one end of the mandrel. Opposing forces are exerted on the tool and the arbor 18, to force the mandrel off the arbor.

When the mandrel 10 slides off the arbor 18, it automatically constricts and returns to its unexpanded state as illustrated in FIGURE 9. It is then a simple matter to unscrew the unitary winding structure from the mandrel (see FIGURE 10). The mandrel 10 of course, is then (ready for use in making another precision resistance winding structure having exactly the same structure and electrical characteristics as that previously formed.

The precision wound resistance winding structure formed as above described may be utilized without change in a potentiometer or variable resistor, with terminals and taps (not shown) seated in appropriate openings and welded to the resistance winding, and a wiper arm positioned within the winding and mounted for longitudinal movement on a shaft which is rotatably mounted on the axis of the helix. If a sturdier structure is desired, the shell 32 may be ground to a smooth cylinder while mounted on the arbor 18, and then, after removal from the arbor (and removal of the mandrel 10) press fit into a cylindrical metal housing 44 having holes 46 aligned with the slot 34 and other holes 48 aligned with the holes 36 and 30 in the shell and strip. The terminals and taps extending through the holes are adapted for connection to an external circuit wiring, all in a conventional manner.

In another embodiment of our invention, the layer of thermosetting material is supplied by initially coating the interior surface of the shell with such material, i.e., the strip of impregnated material is not used. For coating the interior of the shell, we apply a highly thixotropic thermosetting adhesive, e.g., an epoxy resin which is of approximately 0.004" thickness. The shell thus coated is placed around the winding as above described, and the assembly is heated to cause the thermosetting layer to soften and conform to the confronting portions of the winding. Such layer when heated sufficiently wets the winding so that when cooled, it securely bonds the shell and winding together.

From the foregoing, it will be seen that our invention provides a unique precision wound resistance winding for potentiometers and variable resistors of internal design, and a simple and inexpensive method of making such structure which may be reliably repeated to produce precision wound resistance windings in large numbers which have the same structure and electrical properties.

It will be apparent that modifications may be made in our precision wound resistance winding and its method of manufacture without departing from the spirit and scope of our invention. We therefore do not intend that our invention shall be limited except in accordance with the following claims.

We claim:

1. A precision wound electrical resistance winding assembly for potentiometers and variable resistors, comprising:

a preformed helical core with electrical resistance winding thereon;

a longitudinally split insulating shell surrounding said wound core and having an ungrooved inner surface, the ends of said shell defining a slot through which portions of the winding on each core turn are exposed;

and a layer of thermosetting material between the shell and winding which coats and is bonded to the inner surface of said shell and all outer surface portions of said winding except those in said slots, the inner surface of said layer conforming to the various vari-

ations of the outer portions of the turns of said wound core.

2. The assembly of claim 1, wherein said layer includes a strip of glass cloth impregnated with the thermosetting material, the ends of said strip defining a slot aligned with the slot in said shell.

3. The assembly of claim 1, wherein said layer is a coating of thermosetting material on the inner surface of said shell, which coating has been heated to bond said winding to the shell.

4. The assembly of claim 1 further including a cylindrical housing tightly receiving said shell.

5. The assembly of claim 3, wherein said housing has holes therein along the slot in said shell to allow external electrical connection to said winding.

6. The assembly of claim 4, wherein said shell and housing have additional aligned openings angularly spaced

from said slot, and through which to make electrical connection to a portion of the winding adjacent which said additional openings are aligned.
